F. ZALKA

COUNTERWEIGHT FIGURE TOY

Filed May 25, 1927

Frank Zalka
INVENTOR

BY *Victor J. Evans*

ATTORNEY

UNITED STATES PATENT OFFICE.

FRANK ZALKA, OF CHICAGO, ILLINOIS.

COUNTERWEIGHT FIGURE TOY.

Application filed May 25, 1927. Serial No. 194,154.

This invention relates to certain novel improvements in counterweight figure toys and has for its principal object the provision of an improved construction of this character which will be highly efficient in use and economical in manufacture.

Among the several objects of the invention is to provide a toy having its character mounted for oscillation and so arranged to oscillate a considerable period of time and whereby when the oscillatory character is surface decorated an array of brilliant colors will be presented much to the amusement of the child.

15 Other objects will appear hereinafter.

The invention consists in the novel combination and arrangement of parts to be hereinafter described and claimed.

The invention will be best understood by 20 reference to the accompanying drawings, showing the preferred form of construction and in which:

Fig. 1 is a perspective view of the invention.

25 Figure 2 is a fragmentary sectional detail view, of the same, taken substantially on line 2—2 of Fig. 1.

Fig. 3 is a fragmentary sectional detail view of the same, taken substantially on line 3—3 of Fig. 1.

30 Fig. 4 is a fragmentary sectional detail view, of the same, taken substantially on line 4—4 of Fig. 2; and

Fig. 5 is a fragmentary sectional detail 35 view taken substantially on line 5—5 of Fig. 2.

Referring more particularly to the drawing a stand is indicated at 10. This stand includes side walls 11 to which are connected 40 a top wall 12 and bottom wall 13. These walls are connected to the side walls by a tongue and groove connections 14 of a well known type. The top wall 12 has formed therein an elongated slot 15. A body comprising two characters 16 and 17 is formed 45 from a single piece of material preferably of wood of several ply. The character 16 in the present instance is illustrated as an elephant and has its front legs 17' formed as an integral part of the back 18 of the character 17 which character 17 is illustrated 50 as a human being. At the juncture between the back 18 and the legs 17' the character 17 is painted to represent arms 19. The

lower body portion of the character 17 extend downwardly through the slot 15 within the stand 10.

55 The hind legs 20 of the character 16 are pivotally connected to the top wall 12 in the following manner.

To accomplish this, I provide in the preferred form of construction two brackets 21 and 22. These brackets are formed substantially L shaped to provide two base flanges 23 adapted to be arranged in superposed position to dispose openings 24 formed therein in registration with respect to each other for the passage of a connecting element 25, such for example a screw. The brackets secured in this position have their limb portions 26 disposed in spaced parallel relation with respect to each other and in these limb portions, contiguous their upper end portions, are formed openings 27. These limb portions provide outwardly struck portions 75 28 for reasons hereinafter set forth.

70 Formed in the hind legs of the character 16 is an opening 29 substantially elongated in cross section and driven into this opening is a pin 30. This pin 30 may be formed from a flat strip of material with one edge portion 31 thereof finely tapered to provide a substantially small bearing edge 32 slightly rounded in cross section. The end portions 33 of the pin are adapted to fit into the openings 27 with the rounded edge 32 engaging the edges of the brackets providing these 80 openings.

85 Carried by the lower end portion 34 of the character 17 is a weight or bob 35. This weight 35 is preferably formed of metal and is secured to the lower end portion 34 in the following manner:

In molding the weight 35 attaching clips 36 have their end portions 37 embedded in 90 the weight. These clips 36 are substantially U shape to provide limb portions 38 and 39. The outer end portions of these limb portions are bent inwardly and driven into the lower end portion 34 of the character 17, it being noted that the bent end portion of the limb 95 38 being driven into the lower end portion 34 at a point spaced inwardly from the point where the bent end portion of the limb adjacent thereto is driven whereby to prevent weakening of this lower end portion 100 of the body 17.

If desired the characters 16 and 17 may

have their surface decorated with brilliant colors whereby to present an array of contrasted colors during oscillation of the body.

5 In use the characters are initially manually oscillated and by reason of the small bearing edge 32 friction is greatly reduced thus permitting the characters to oscillate a substantial period of time.

10 It will be seen that the structure is such that the toy may be disassembled for packing into a compact parcel. By forming the characters from wood of several ply it will be manifest that cracking or breaking of the characters cannot easily take place.

15 While I have illustrated and described the preferred form of construction for carrying my invention into effect, this is capable of variation and modification, without departing from the spirit of the invention. I, therefore do not wish to be limited to the 20 precise details of construction set forth, but desire to avail myself of such variations and modifications as come within the scope of the appended claim.

25 Having thus described my invention, what

I claim as new and desire to protect by Letters Patent is:

A toy comprising a supporting structure having a top wall provided with an elongated slot, oppositely disposed brackets secured 30 to said top and having openings formed in parallel limb portions and extended portions adapted to be bent to obstruct passage through the openings, a character having a body portion provided with an opening 35 formed substantially elongated in cross section, a pin fitted into said opening and formed substantially elongated in cross section and having an edge portion tapered and rounded to provide a restricted bearing surface, said pin being adapted to have its end portions mounted in said openings, a bob, and a character including an extended portion extending downwardly through the slot and carrying the bob, said second mentioned 45 character being formed integral with said first mentioned character.

In testimony whereof I affix my signature.

FRANK ZALKA.
